(57) **CLAIM**

I claim the ornamental design for a capsule, as shown and described.

DESCRIPTION

FIG. 1 is a first perspective view of a capsule showing the new design;

FIG. 2 is a top plan view thereof;

FIG. 3 is a left side elevation view thereof;

FIG. 4 is a bottom plan view thereof;

FIG. 5 is a right side elevation view thereof;

FIG. 6 is a front elevation view thereof; and,

FIG. 7 is a rear elevation view thereof.

The broken lines illustrate portions of the capsule that form no part of the claimed design.
